FRANK E. RICE.
By Frank E. Rice

UNITED STATES PATENT OFFICE.

FRANK E. RICE, OF DETROIT, MICHIGAN, ASSIGNOR TO AMERICAN TAP BRUSH CO., A CORPORATION OF MICHIGAN.

ORIFICE CAP.

Application filed May 20, 1922, Serial No. 562,299. Renewed August 29, 1925.

To all whom it may concern:

Be it known that I, FRANK E. RICE, a citizen of the United States, and a resident of the city of Detroit, in the county of Wayne and State of Michigan, have invented certain new and useful Improvements in an Orifice Cap; and I do hereby declare that the following is a full, clear, and exact description of the same, reference 5 being had to the accompanying drawings, and to the numerals of reference marked thereon, which form a part of this specification.

This invention relates to an orifice cap 15 adapted for closing the orifice in a gasoline tank or the like.

It is an object of this invention to provide a cap comprising a pair of separable sections which are assembled by relative 20 rotation and clamped together, the structure being such that reverse rotation under clamping action is resisted. The invention further contemplates clamping mechanism which is readily operable, and in which there 25 is no tendency to stick or jam of parts, and which comprises certain yieldable features for the operating element thereof, as will be more readily apparent in the following description and disclosure.

30 This invention comprises the novel mechanism and combinations hereinafter described and more particularly pointed out in the appended claims.

In the accompanying drawings, which 35 illustrate a preferred embodiment of this invention, and in which similar reference numerals refer to similar parts in the different views:

Figure 1 is a section through a tank, showing 40 my improved cap partly in section and partly in elevation applied over the orifice therein.

Figure 2 is a fragmentary top plan view of the cap applied to the tank.

45 Figure 3 is a section on the line 3-3 of Figure 2 upon an enlarged scale.

Figure 4 is a section on the line 4-4 of Figure 2.

50 Figure 5 is a top plan view of the lower section.

Figure 6 is a bottom plan view of the upper section.

55 Figure 7 is a section on the line 7-7 of Figure 1, upon an enlarged scale.

Figure 8 is a fragmentary sectional view 55 of a modification upon a reduced scale.

Figure 9 is a plan view of a spring used in my modified form.

As shown on the drawings:

In referring now to the drawings, which 60 illustrate one embodiment of this invention, the reference numeral 1 represents a tank or vessel having an orifice 2 over which my improved cap fits. The cap may be bolted or welded to the tank in any approved way. 65 The cap consists of a pair of separable sections 2 and 3, the former constituting the upper or removable section and the other constituting the lower or stationary section.

The lower section 3 is illustrated as of 70 cylindrical form made of sheet metal and provided with an attaching base in the form of an annular flange 4. Adjacent the upper margin of the section, an inwardly directed channel-shaped groove 5 is stamped in the 75 metal. The upper wall or flange 6 of this groove is cut away preferably upon opposite sides as indicated at 7 (Fig. 5) to provide entrance slots or notches, and a portion of the cut-away part is bent downwardly at 80 one end of each notch and across the groove to provide a stop 8 whereby the channel-shaped groove 5 is divided into two parts, which may be said to constitute two separate grooves, each of which extends substantially 85 upon an arc of 180°. The upper wall of each groove is cut away or beveled upwardly toward its inner end adjacent the stop 8 forming an upwardly extending slope or depression, as indicated at 9 (Fig. 4); that 90 is, the upper walls of the two grooves slope upwardly toward the stops 8. The walls 6 may be either cut away or pressed upwardly for this purpose.

The upper section 2 is also of cylindrical 95 form and preferably stamped from sheet metal in the form of a hood with inwardly directed lugs 10 adapted for entering the notches 7 of the lower section. The upper surfaces of these lugs are biased upwardly 100 from the front end toward the rear as shown in Fig. 4. Centrally of the top of the section, there is an integral neck 11 stamped therein for receiving a screw-threaded plug 12 in which a hand-operated screw 13 is inserted. The lower end of this screw is secured to a resilient or spring plate 14 of 105 circular form having notches 14a (Fig. 6)

at opposite sides for receiving the lug 10 whereby the plate is adapted for insertion in said section and then rotated therein before its attachment to the screw. Below 5 the resilient plate 14, a circular fibrous or frictional member 15 is inserted in the said upper section normally lying above the lugs 10. Instead of using the screw 13, a four-point spring 16 (Fig. 9) may be positioned 10 in the upper section which in the modified form is shown closed at the top so that the top 17 of the spring will rest against the interior surface thereof with its four downwardly diverging arms which define the four 15 bearing points resting upon the top of the plate 14.

The upper section of the cap is applied or removed from the lower section by a rotational movement, as is obvious. In applying 20 the upper section, the lugs 10 are passed through the slots or notches 7 into their respective grooves, as shown in Fig. 7. Then by turning the upper section in an anti-clockwise direction, the lugs 10 will 25 pass under the flange 6, i. e., the upper walls of their respective grooves, until they strike the stops 8. During this operation it is of course presumed that the plate 14 is sufficiently adjusted in an upward direction 30 so as not to interfere with the operation of applying the upper section. When the upper section has been applied as above explained, it will be in the position illustrated in Fig. 4 and in dotted lines in 35 Fig. 7 with the lugs 10 adjacent the stops 8, and in order to press the lugs against the slopes of the walls 6, the screw 13 is turned to force the frictional member 15 tightly against the upper edge of the lower 40 section, whereby the upper section will be slightly raised in an axial direction of the screw whereby the lugs will be pressed with a tight frictional fit against the slope of the walls 6 and a braking action will be 45 applied to the upper section so there will be very little tendency for relative rotation of the sections until the pressure on the screw is released for again removing the upper section.

50 In the modified form, the upper section is forced down into position upon the lower section against the tension of the spring and then rotated. When the lugs reach the 55 depressions 9, the force of the spring will slightly elevate them, whereby greater frictional resistance will have to be overcome in unscrewing the upper section, so the sections might be said to be yieldingly clamped together.

60 It should be noted that in screwing down the screw 13, the plate 14 will yield, and the yielding force will be directed in an upward direction, so the screw 13 will never 65 become so tightly wedged or jammed in its clamping position that it cannot be readily

removed. In the use of such a resilient plate, the screw becomes readily responsive for unclamping purposes.

I am aware that numerous details of construction may be varied through a wide 70 range without departing from the principles of this invention, and I therefore do not purpose limiting the patent granted otherwise than necessitated by the prior art.

I claim as my invention:

75 1. A closure cap for an orifice comprising a pair of relatively rotational sections, one of said sections having a pair of grooves with entrance notches, one wall of each groove being beveled at its inner end, the other section having lugs beveled upon one surface for cooperating with the beveled walls of said grooves and adapted for insertion through said notches, and means for frictionally clamping said sections together 80 against relative rotation.

85 2. A closure cap for an orifice comprising a pair of relatively rotational sections, one of said sections having grooves and the other section having lugs for entering said 90 grooves, one of the walls of each groove being cut away adjacent the inner end thereof, and means for clamping said sections together by relative longitudinal movement thereof with the lugs of one section in the cut-away portions of the grooves of the other section.

95 3. A closure cap for an orifice comprising a pair of relative rotational members, the lower section having a groove and the upper section having a lug for entering said 100 groove, a frictional member in the upper section, a resilient plate above said frictional member, and a screw threaded into said upper section and secured to said plate, said screw being operable for clamping said frictional member upon the upper section whereby said lug will be tightly 105 drawn against the upper wall of said groove.

110 4. In a device of the class described, a lower cylindrical cap section adapted for attachment over an orifice and having grooves stamped therein with entering notches extending from its upper margin, an upper section having inwardly directed 115 lugs stamped therefrom adapted for entering said notches and grooves of the lower section, a frictional member in the upper section, a resilient plate resting upon the upper surface of said frictional member, a screw member threaded into the top of said upper section and secured to said resilient plate, said screw being operable for clamping said frictional member upon the lower section and drawing said lugs into 120 frictional contact with the upper walls of said grooves.

125 5. In a closure cap for an orifice, a pair of separable and relatively rotational members having coacting parts engageable by rel-

ative rotation thereof, and means embodying a manually actuated screw for frictionally locking said members against relative rotation.

5 6. In a closure cap for an orifice, a pair of separable and relatively rotational members having mutually engageable parts adapted to be brought into coacting relation

through relative rotation thereof and manually operated means for causing said engageable parts to become frictionally locked against rotation.

In testimony whereof I have hereunto subscribed my name.

FRANK E. RICE.
